[57] CLAIM

The ornamental design for a combined voice and data terminal or similar article, substantially as shown and described.

DESCRIPTION

FIG. 1 is a front isometric view of a combined voice and data terminal or similar article showing our new design;

FIG. 2 is a rear isometric view thereof;

FIG. 3 is a front elevational view thereof on an enlarged scale;

FIG. 4 is a rear elevational view thereof on an enlarged scale;

FIG. 5 is a left side elevational view thereof on an enlarged scale;

FIG. 6 is a right side elevational view thereof on an enlarged scale;

FIG. 7 is a top plan view thereof on an enlarged scale; and

FIG. 8 is a bottom plan view thereof on an enlarged scale.
